Specification for Design.

Patented Apr. 6, 1915.

Application filed July 13, 1914. Serial No. 850,830. Term of patent 14 years.

To all whom it may concern:

Be it known that we, JOHN A. ABEL and EDWARD C. ABEL, both citizens of the United States, residing at Woodhaven, in the county of Queens and State of New York, have jointly invented a new, original, and ornamental Design for Pendants, Bar-Pins, Bracelets, Scarf-Pins, or Similar Articles, of which the following is a specification, reference being made to the accompanying drawing, forming part thereof.

In the drawing, the figure is a plan view of a pendant showing our new design.

Copies of this patent may be obtained for five cents each, by addressing the "Commissioner of Patents, Washington, D. C."

We claim:—

The ornamental design for a pendant, bar pin, bracelet, scarf pin, or similar article, as shown.

In witness whereof, we have hereunto signed our names in the presence of two subscribing witnesses.

JOHN A. ABEL.
EDWARD C. ABEL.
